UNITED STATES PATENT OFFICE.

EUGENE A. LYMAN, OF MOUNT VERNON, NEW YORK.

DEMOUNTABLE RIM.

1,264,827.

Specification of Letters Patent. Patented Apr. 30, 1918.

Application filed June 8, 1917. Serial No. 173,437.

To all whom it may concern:

Be it known that I, EUGENE A. LYMAN, a citizen of the United States, residing at Mount Vernon, in the county of Westchester and State of New York, have invented certain new and useful Improvements in Demountable Rims, of which the following is a full, clear, and exact description.

This invention relates to demountable rims having integral straight side flanges, and more particularly to rims of this character which are made in sections to facilitate the assembling of the rim and tire.

The objects of the invention are to provide a rim of this character which is of a simple construction, is constructed from a minimum number of sections, is capable of being manipulated for rapid assembling, and when assembled has its sections rigidly locked together to hold the shoe in position.

Other objects of the invention will be clear from the detailed description herein-after to follow, taken in connection with the accompanying drawings and will be particularly pointed out in the appended claim.

In the drawings:

Figure 1 shows in elevation a rim constructed in accordance with the principles of the invention;

Fig. 2 is an elevation of the rim shown in section in partially assembled position;

Figs. 3 and 4 are details of the locking plate and stud utilized at one end of the short section; and

Figs. 5 and 6 are details of the locking stud at the other end of the short section.

The demountable rim, which is adapted to be placed over the felly of the wheel of the vehicle after the shoe has been placed in position thereon; is of the usual type of demountable rim, in which the straight side flanges are integral with the body of the rim, but instead of being split at one point, as is the usual construction of these rims, it is made in two sections 1 and 2, of unequal lengths, the section 2 being the short section, which is assembled after the long section 1 has been placed within the shoe.

The sections 1 and 2 are rigidly locked together when in assembled position by locking plates and studs, which are constructed to permit the rapid assemblage of the rim and shoe and also the removal of the rim from the shoe when necessary. The locking plates are secured to the short section 2, and are designated 3 and 4. These plates

consist of short rectangular strips of sheet steel which are riveted as at 5 to the inner face of the short section 2 at the ends thereof, so that they project beyond the ends of the short section to overlap the ends of the long section 1 when the section 2 is in position. One corner of the plate 3 may be cut away as at 5'. Secured to one end of the inner face of the long section 1 is a stud 6 which is adapted to pass through a hole or opening 7 in the projecting end of the plate 3. This stud is of greater length than the thickness of the plate 3 so that it projects beyond this plate, as shown in Fig. 3, the end of the stud being preferably pointed, as shown, to aid in the assembly of the sections, as will be later referred to.

The locking plate 4 at the other end of the section 2 also co-operates with a locking stud which is designated 8, which stud passes through a hole or opening 9 in a projecting end of the plate. The outer wall of the opening 9 and the engaging face of the stud are undercut at 10 to prevent the plate from slipping off the stud when the rim is mounted upon the wheel felly and an outward pressure is placed upon the rim by the usual wedges which are utilized to maintain the rim in place on the wheel.

In order to make the sections rigid when locked, it is desirable to make the short section as nearly the same size as the long section, and yet permit the sections to be assembled with ease and facility without requiring the short section to be sprung into place, and in the method of assembling described the short section is so proportioned. To insert the shoe upon the rim, the section 1 is first positioned within the shoe, which may be readily accomplished by placing one end of the section within the shoe and then bending the section slightly until the other end is depressed sufficiently to permit it to be freely inserted into the shoe. The section 2 is then placed in position by placing the hole 7 in the plate 3 over the stud 6, which can be readily accomplished, since this stud has a pointed end. The section 2 is then swung upon the stud 6, as a pivot, to bring it into alignment with the section 1, but which necessitates tilting it upon the plate 3 to bring the edge of the flanges of the short section beneath the body of the section 1, as shown in Fig. 2. It is for this purpose that the corner of the plate 3 is cut away, as at 5, since the plate will then rest

upon this cut-away portion while being tilted. The sections are then in the position shown in Fig. 2, the section 2 is then pulled outwardly until it is in engagement with the shoe, which will also cause the stud 8 to pass into the hole 9 to lock the two sections together. The demountable rim is ready to be placed upon the felly of the wheel, where it is secured in place in the usual manner, by wedges fitting between the felly of the wheel and the demountable rim. Any outward pressure which is placed upon the section 2, which pressure might cause the stud 8 to slip out of the hole 9, is prevented by undercutting the stud 8 and wall of the hole, as described.

To remove the rim from the shoe, the short section is pressed inwardly until the plate 4 is free from the locking stud 8, after which the short section may be removed by swinging it the reverse of the assembling operation. The long section can then be removed without difficulty.

It is to be understood that a valve hole 11 is provided in the section 1 through which the tire valve is inserted when initially assembling the tire upon the section 1, as described.

It will therefore be seen that the rim may be assembled and removed from a shoe without requiring any tools, such as tire irons, and either operation can be performed in an entirely simple and rapid manner.

The assembled tire and rim are then positioned upon and locked to the wheel of the vehicle in the usual manner, the long stud 6 fitting in a suitable recess in the felly of the wheel, which will prevent the rim from slipping around the wheel. The wedges which are interposed between the felly of the wheel and the rim will cause a slight extending of the sections, bringing the undercut stud 8 into locking engagement with the wall of the hole. This slight expanding of the rim forces it into firm engagement with the shoe which will prevent any slippage of the tire upon the rim.

I claim:

A demountable rim comprising a long and a short section, fixed locking plates projecting from the ends of said short section having holes therein, locking studs carried by the long section adapted to fit into said holes to lock the said sections together, and one of said studs and the walls of the hole in engagement therewith being undercut and another of said studs being of a greater length than the thickness of said plate and serving as a pivot for swinging the short section into position.

In witness whereof I subscribe my signature in the presence of two witnesses.

EUGENE A. LYMAN.
